UNITED STATES PATENT OFFICE

150,412

DESIGN FOR A MICROFILM VIEWER

Herman L. Gordon, Silver Spring, Md.

Application January 27, 1947, Serial No. 136,456

Term of patent 14 years

(CL. D61—1)

To all whom it may concern:

Be it known that I, Herman L. Gordon, a citizen of the United States, residing at Silver Spring, in the county of Montgomery and State of Maryland, have invented a new, original, and ornamental Design for a Microfilm Viewer, of which the following is a specification, reference being had to the accompanying drawings, forming part thereof.

Figure 1 is a side elevational view of a microfilm viewer showing my new design.

Figure 2 is a front elevational view of the microfilm viewer of Figure 1.

Figure 3 is a cross-sectional view taken on line 3—3 of Figure 1 and looking in the direction of the arrows thereof.

Figure 4 is a cross-sectional view taken on line

4—4 of Figure 1 and looking in the direction of the arrows thereof.

I claim:

The ornamental design for a microfilm viewer, as shown.

HERMAN L. GORDON.
